Patented Nov. 14, 1916.

By his Attorney

Ludwig Wertheim Inventor
Jacob B. Arens

UNITED STATES PATENT OFFICE.

LUDWIG WERTHEIM, OF NEW YORK, N. Y.

DESIGN FOR A HAND-BAG.

49,914.

Specification for Design.

Patented Nov. 14, 1916.

Application filed September 16, 1916. Serial No. 120,577. Term of patent 3½ years.

To all whom it may concern:

Be it known that I, LUDWIG WERTHEIM, a citizen of the United States, residing at New York, in the county of New York and State of New York, have invented a new, original, and ornamental Design for Hand-Bags, of which the following is a specification, reference being had to the accompanying drawings, forming part thereof.

The figure is an end elevation of the hand-bag showing my new design.

I claim:

The ornamental design for a hand-bag as shown.

LUDWIG WERTHEIM.
